UNITED STATES PATENT OFFICE

SHERROD RIDDEL, OF SPRINGFIELD, ILLINOIS, ASSIGNOR OF ONE-HALF TO PERRY
EDGAR SPAULDING, OF SPRINGFIELD, ILLINOIS

SAFETY HAND STARTER FOR GAS ENGINES

Application filed November 9, 1929. Serial No. 405,942.

This invention relates to improvements in the starting devices for internal combustion engines, particularly to a safety crank or hand starter for such engines, and it is the 5 principal object of my invention to provide a device of this character which will positively prevent injury to the operator in case the engine starts in the wrong direction or backfires.

10 It is a well known fact that the sudden reversing of the crank handle by a backfire of the engine during starting has broken the wrists of many operators and caused other injuries. My invention will avoid all these 15 disadvantages and effectively protect the operator against injury if the engine starts in the wrong direction by simple and therefore inexpensive devices which may be readily applied to any car without the necessity of material changes therein.

20 A further object of my invention is the provision of a device of this character which is durable and efficient in operation.

With these ends in view I provide a starter 25 with means for automatically disengaging the starting lever from the starter shaft as soon as the engine is started in the wrong direction and reverse rotation occurs.

These and other objects and advantages of 30 my invention will become more fully known as the description proceeds, and will then be specifically defined in the appended claims.

In the accompanying drawing, forming a material part of this disclosure:

35 Fig. 1 is a sectional plan view of an engine starter constructed according to my invention.

Fig. 2 is a side elevation thereof at a right angle to the showing in Figure 1.

40 Fig. 3 illustrates the starter used with electric engine starting devices.

Fig. 4 is a fragmentary sectional detail view through the crank operated bevel gear and ratchet.

45 As illustrated, a frame 10 with which is connected by means of bolts 10' or the like passing through a conventional starter bracket 11' attached to the crank case of the engine, a bracket 11 in which the one end of

50 a shaft 12 is journaled carrying at its lower

end a bevel gear 13 in mesh with a bevel gear 14 on a shaft 15.

Shaft 12 carries a starter worm 16 held thereon by means of a set screw 17, and a standard starter gear 18 which is in mesh with the flywheel ring gear 19. The bevel gear 14 has integrally formed therewith a ratchet 20 screwed on quick threads formed on part of shaft 15 and fixedly secured thereto. A lever 21 is movably arranged on 60 shafts 15 and carries a pawl 22 and is held against ratchet 20 by means of a spring 23.

Near its inner end shaft 15 carries a ratchet 24 engaged by a pawl 25 which allows a rotation of the ratchet 24 in one direction only, 65 and pawls 22 and 25 are held in engagement with ratchets 20 and 24 respectively by conventional springs.

The device operates as follows:

When it is desired to start the engine, the 70 crank lever 21, ratchet 20 and its bevel gear 14 are turned by the intermediary of pawl 22 and bevel gear 13 in mesh with gear 14 will be rotated and rotate shaft 12.

The rotation of shaft 12 by the intermediary of gear 18 in mesh with flywheel ring gear 19 will crank the engine starter shaft. If the engine starts in the proper direction of rotation, gear 18 is screwed out of mesh with the flywheel gear 19 in the conventional manner.

If however, the engine backfires or starts in the wrong direction shaft 12 and bevel gear 13 will be turned in a direction opposite to normal and gear 14 will also be reversed, 85 ratchet pawl 25 on account of its engagement with the teeth of ratchet 24 will prevent ratchet 24 from turning in the wrong direction and thus also prevent shaft 15 from turning in the wrong direction, and ratchet gear 20 and bevel gear 14 will be moved outward along the threads on shaft 15 until gear 14 becomes disengaged from bevel gear 13 and further rotation of lever 21 will be prevented even if shaft 12 executes several revolutions. Spring 23 will hold lever 21 securely in place to allow an operation of ratchet 20 and bevel gear 14.

It will be clear that my device may be designed to replace a standard electric motor

starter or it may be designed as a substitute for a conventional hand crank.

It will be understood that I have described and shown the preferred form of my device 5 only as one example of the many possible ways to practically construct the same, and that I may make such changes in its general arrangement and in the construction of the minor details thereof as come within the 10 scope of the appended claims without departure from the spirit of my invention and the principles involved.

Having thus described my invention, what 15 I claim as new and desire to secure by Letters Patent is:

1. In a hand starter for internal combustion engines, a main shaft, a bevel gear at one end of said shaft, an auxiliary shaft, a bevel gear on said auxiliary shaft in mesh 20 with the bevel gear on the main shaft, a lever on said auxiliary shaft, a threaded part on said auxiliary shaft, a ratchet gear on said auxiliary shaft integral with the bevel gear on the same, a pawl on said lever in engagement with said ratchet gear, a spring wound about said auxiliary shaft for normally holding said lever in engagement with said ratchet gear to allow a cranking of the engine, a second ratchet gear in engagement with the 25 threaded part of said auxiliary shaft, and a means cooperating with said second ratchet gear for locking said auxiliary shaft against reverse rotation the locking action effecting a longitudinal movement of said integral 30 ratchet and bevel gear on the threaded part of the auxiliary shaft, adapted to separate the bevel gears on the main shaft and the auxiliary shaft to prevent rotation of the crank in the reverse direction upon the occurrence of back fire in the engine.

2. In a cranking device for the shafts of internal combustion engines, a main shaft, a bevel gear at one end of said main shaft, an auxiliary shaft, a bevel gear on said auxiliary shaft normally in mesh with said bevel gear on the main shaft a lever on said auxiliary shaft, a ratchet wheel on said auxiliary shaft integral with the bevel gear on said shaft, a second ratchet on said auxiliary shaft, a pawl in engagement with said second ratchet to permit its rotation in one direction only, a worm on the part of the auxiliary shaft carrying the integral ratchet and bevel gears, and a spring wound about another part of the auxiliary shaft for normally holding said lever in engagement with said ratchet wheel on the auxiliary shaft, whereby said second ratchet, cooperating with its pawl, is effective to lock said auxiliary shaft against reverse rotation and said locking action is effective to cause separation of the bevel gears on the main and the auxiliary shafts, said bevel and ratchet gear moving longitudinally along said auxiliary shaft away from the main shaft.

Signed at Springfield, in the county of Sangamon and State of Illinois this 4th day of November A. D. 1929.
